HOSIERY

Edward W. Boedeker, Fort Wayne, Ind.

Application June 3, 1944, Serial No. 538,594

1 Claim. (Cl. 66—187)

1

This invention pertains to stockings and more particularly to a woman's stocking formed by a single operation, said stocking to be of any knitted texture such as a smooth, regular knit, mesh, non-run, etc.

In knitting stockings it has been usual to knit the leg portion of the stocking in one operation on a conventional leg knitting machine, the leg of the stocking being knitted substantially flat, the edges which ultimately are sewn together, to form the back seam being suitably shaped in the well known manner on said machines. The leg portion is also formed on said machine providing depending heel portions or tabs so that the stocking at this point in its formation is substantially U-shaped when placed in flattened condition.

Having formed this portion of the stocking, it is then necessary to put the article on a footer to form the sole, instep and toe portions. It will thus be appreciated that it is necessary to accurately place on the footer the portion of the stocking completed during the first step. Otherwise, there is a danger that there will be a mismatching of the contours of the heel and sole reinforcements, causing an unsightly foot. Further it is necessary that the adjustment of the legger and footer be the same, or there will be a difference in the character of the knitting in the leg and foot causing the above referred to shading.

In completing this type of stocking, it is necessary to loop or close the toe and heel. It is then necessary, as a distinct step, to seam the sole (between the toe and heel) and then, as a final step, the leg is seamed. With this type of stocking there is the additional danger that the heel will be ill-fitting, that there will be projections or ears at each side of the heel where it is looped, and further, that there will be a thickened seam where the looping and the seams join. Not only that, but with this type of stocking it is difficult to obtain a symmetrical contour on the upper edge of the high-splicing of the heel, for example, where the upper edge is designed to be absolutely perpendicular to the seam. In such type of stocking, when completed, there is the danger that this edge will be angularly disposed with respect to the seam, and, as a matter of fact, it is rarely of proper design contour. In completing this type of stocking it will additionally be appreciated that, inasmuch as the toe and heel are looped prior to the seaming (and the seaming and looping are done on different machines), it is necessary for the seaming operation to remove the stocking from the seaming gauge after one seam has been put in the foot, and then reinsert

5 the stocking in the seaming gauge for forming the final seam in the leg. This multiplicity of operations makes for slower production and increases the chances for mistakes in the final completion, and further increases the opportunity for damage to the stocking due to the number of times the stocking must be handled. In this type of stocking it is also to be kept in mind that in the completed garment the wales in the leg and heel are substantially coextensive. The wales in the instep portion substantially follow the instep, but the wales in the sole and toe are substantially at right angles to the wales in the leg and heel, particularly in a woman's stocking, and the 10 contour of the foot is not followed, nor can the heel pocket be accurately formed, so that there is the danger of bunching of the material under the heel, which is not only unsightly, but uncomfortable.

15 20 Attempts have been made to form a stocking by a single operation. By "single operation" is meant the complete forming of the stocking on a single machine without the necessity at any time of removing the stocking from the machine, 25 from the start of the leg portion to the completion of the toe portion. However, such one operation stockings have required special machines of expensive operations. In order to form certain operation stockings, a multiplicity of narrowing fingers is required which, in the completed stocking, causes the wales in the heels to run in a plurality of directions, thereby affecting the fit of the heel. Due to the multiplicity of narrowing fingers necessary on the knitting machine, it 30 is necessary to employ complicated mechanism for effecting the operation of said fingers which, 35 of course, is expensive.

40 In another type of single operation stocking, the heel pocket is formed by progressively rendering the outer needles inoperative, that is, the successive dropping of stitches. This, of course, is objectionable in that there is a danger of runs taking place from the heel seam, unless all of the stitches are accurately and correctly located, and further, difficulty is encountered in properly forming the top contour of the heel. Not infrequently the top of said contour takes the formation of a flattened V instead of a horizontal straight line. Also in this type of stocking it is 45 to be noted that the wales in the heel sweep around the contour of the heel, which prevents proper fitting.

50 55 In the finishing of the stocking in accordance with the herein contemplated method, the above objections are eliminated. The stocking is made

2

on a single machine utilizing a relatively inexpensive means for forming the heel of the stocking. Certain wales of the leg and heel are co-extensive and the sole wales are disposed substantially at an angle of 60° to the wales of the heel. Narrowing and widening operations are effected in a predetermined manner in knitting the stocking, so that the completed stocking more accurately follows the contour of the foot and more accurately, and more snugly fits the foot so that there is no objectionable or uncomfortable bunching of material under the heel or at any other place. The configuration of the heel can be accurately determined so that the upper line of the heel is exact, that is, it is exactly in line and perpendicular to the seam, and there can be, of course, no mismatching of any of the parts of the stocking, as it is completely made on a single machine, and thus there is no danger of a difference in the knitting, nor is there a chance that there will be a difference in the material, as may happen as above pointed out in the case of the conventional stocking.

In addition to this, in completing the stocking, a single machine may be used in a continuous operation for forming the seam in both the leg and foot, thus eliminating the above referred to looping operations at the heel. This, of course, not only makes for less handling of the stocking, but permits the speeding up of the seaming operations, as there is no discontinuing of one seaming step and continuing of another seaming step, as is necessary as above explained with respect to the first referred to process.

It is therefore an object of this invention to provide a single operation stocking which can be knitted on a single machine.

Another object is to provide a single operation stocking of any knitted texture such as a smooth regular knit, mesh, non-run, etc.

Still another object is to provide a single operation stocking which closely fits the foot and in which the wales of the foot are disposed at an angle other than 90 degrees to those in the heel.

Yet another object is to provide a single operation stocking where the foot and leg seams are continuous and uninterrupted.

A further object is to provide a single operation stocking which can be knit on conventional machines now in use with only the addition of a relatively inexpensive control means therefor.

A yet further object is to provide a single operation stocking where the wales in the foot are disposed at an angle of substantially 60 degrees to those in the heel to thereby insure better fitting of the wearer's heel.

Another further object is to provide a stocking wherein a widening operation takes place over the entire heel by controlled operation of the narrowing fingers and carriers of the knitting machine.

A different object is to provide a stocking which can be knitted on only one machine, obviating the danger of mismatching.

Another different object is to provide a single operation stocking wherein a perfectly smooth and close fitting heel is attained and one which may be completed by a minimum of handling operations, i. e., it is only necessary to loop the toe and sew the remainder of the stocking.

Another object of the invention is to provide a single operation stocking wherein the shaping of the heel is more easily and accurately controlled.

Another object of the invention is to provide a

single operation stocking wherein various shapes of heels can be knitted on a single machine without extensive changes being made to the mechanism of the machine.

With these and various other objects in view, the invention may consist of certain novel features of construction and operation as will be more fully described and particularly pointed out in the specification, drawings and claim appended hereto.

In the drawings, which illustrate an embodiment of the invention, and wherein like reference characters are used to designate like parts—

Figures 1 to 4 inclusive, are fragmentary side elevations of modified forms of stockings showing foot, heel, and a portion of the leg, in flattened condition, showing in a somewhat diagrammatic manner the disposition of the wales, the spacing of the wales being exaggerated for the sake of clearness.

Figure 5 is a fragmentary, partly interrupted section of a stocking, showing the disposition of the knitted loops in the formation of the stocking illustrated in Figure 1, from a point which is prior to the start of the heel, and extending around said heel and into said sole, and for the distance of the sole narrowing, the bottom of said view being prior to the heel.

Figure 6 is an enlargement of the knitted loops forming one of the apertures of the gore line.

Figure 7 is an enlargement of the knitted loops showing the disposition of the loops obtained by the heel narrowing.

Figure 8 is an enlargement showing the looping obtained in knitting occasioned by the sole narrowing.

Figure 9 is a fragmentary perspective elevation showing a form of main narrowing and widening fingers, together with the associated auxiliary fingers as applied to one form of knitting machine (H. S. L. type machine).

Figure 10 is a fragmentary perspective elevation showing a form of main narrowing and widening fingers, together with the associated auxiliary fingers as applied to another form of knitting machine (Reading type machine using the lace rods equipped with the auxiliary widening fingers).

Referring first of all to the stockings illustrated in Figures 1 to 8 inclusive, the top (not shown) and leg 20 are knitted in the conventional manner to the start of the high splicing 22 (which defines the start of the reinforcing carried through the heel, sole, and toe), the reinforcing thread being operative at the start of the high splicing, and the size of the stitching being increased due to the use of the reinforcing thread. This type of knitting is continued until the start of the heel at 24 at which point, or course, there is a widening caused by a controlled outward movement of the main narrowing and auxiliary widening fingers operating as a single finger.

In Figure 9 there is illustrated a plurality of narrowing finger rods 26 to which are supported the inner, main narrowing and widening fingers 28 provided with the usual narrowing and widening needles 30. Outer auxiliary widening fingers 32 provided with widening needles 34 are disposed outwardly of the fingers 28 and closely adjacent thereto, and are supported on the narrowing rods. In the form of device illustrated in Figure 10, the finger rods 36 respectively support the inner, main narrowing and widening fingers 38 having the needles 40 thereon and the adjacent lace rods 42 are provided respectively with

outer auxiliary widening fingers 44 having needles 46 thereon, said fingers 44 being disposed adjacent the respective fingers 38, and being adapted to be moved out of operative position by rotation around the respective lace rods 42.

In the knitting of the stocking down to the end of the usual leg narrowing mark (not shown) it has been found convenient to use substantially three-fourths of an inch of the fingers 28 or 38, the use of the fingers being then discontinued until the course starting the heel, which is the course at 24, at which point the widening begins and the entire width of the fingers (28—32 or 38—44) is utilized. The width of the combined fingers may conveniently be two inches wide while the width of the auxiliary fingers (32—44) are substantially three-fourths of an inch. The above referred to proportions of the fingers may, of course, be suitably changed and are merely given here by way of illustration.

Thus at the point 24 of the stocking, i. e., at the start of the heel, both the narrowing and widening fingers and auxiliary fingers (28—32; 38—44) are operative together. It is understood, of course, that two sets of fingers are used on each knitting head, said head knitting a single stocking. At the point 24, the size of the stitch is again increased so that it is larger than the size of the stitch beginning at the start of the high splicing, as at 22, the increase of the stitch at the point 24 in effect permitting a better fitting heel pocket to be formed.

As above pointed out, at the start of the heel at 24 both fingers (28—32 or 38—44) are utilized and the yarn carriers move outwardly, outward movement of the narrowing fingers taking place over a distance equal to one needle spacing while the carriers are moved over a distance of two needle spacings causing the formation of a stitch such as illustrated in Figure 6, and as the knitting continues aligned apertures 52 are formed whereby in the completed stocking a gore line 54 is formed of said aligned apertures. It is understood that the narrowing fingers are moved first a distance equal to that between two adjacent needles, termed one needle spacing, but in order to complete the outside wales in unbroken alignment (to the point or course 48), that is, to prevent discontinuance of the wales, which would happen if the fingers did not catch up to the carriers, the fingers are thereafter moved an additional distance equal to one needle spacing (to thereby move the narrowing fingers a distance equal to that moved by the carriers) after the carriers have moved through one or more courses, that is, have moved laterally through a complete stroke or course.

At the course 48 which is the start of the heel mock fashioning or heel mock fashioning mark 58, the carriers no longer move outwardly, and outer fingers 32 or 44 have been rendered inoperative as above pointed out, and at that point the inner fingers 28 or 38 still continue to move outwardly in the same manner that they have been moving outwardly, continuing the formation of an aperture 52 (Figure 5) in alignment with prior aperture 52 to a predetermined point or course 50 forming the straight unbroken gore 54. The mock fashioning mark 58 caused by the outward movement of fingers 28 or 38 between courses 48 and 50 set over a distance equal to the space between two needles, that is, one needle spacing. As fingers 28 or 38 are moved outwardly between courses 48 and 50 and as the carriers no longer move outwardly during the formation of

the courses between 48 and 50, knitting takes place to the edge 56 of the stocking, and the heel mock fashioning or mark 58 is formed between courses 48 and 50, the stitch thereof appearing as illustrated in Figure 7, it being seen that the gore line 54 extends to the course 50 and it also is seen that the knitting of the edge continues forming a clean edge where no stitches are dropped. In other words, the outward movement of the fingers causing the narrowing is determined by the length of mark 58 which must terminate before the edge is reached, otherwise there are no continuous edge wales, and stitches could be dropped, or runs occur.

Referring now particularly to Figures 1 and 5 to 8 inclusive, after course 50, the sole narrowing begins, this is effected by utilizing a predetermined number of needles of the inner fingers 28 or 38, for example, in the stocking illustrated, utilizing about three-fourths of an inch of the inner needles. This narrowing takes place for a predetermined distance, forming the sole narrowing mark 60, one of the stitches of said mark 60 being illustrated in Figure 8. After the ending of the mark 60, the remainder of the stocking is knitted in the conventional manner and it will be seen that the reinforcing of the high splicing is carried inwardly of the gore 54 and mark 60. Certain of the edge wales 62 extend down the leg, around the heel and for the length of the foot portion, others of said wales 64 extend down the leg, around the heel and terminate in the mark 58. Certain of the wales 66 inwardly of the mark 58 extend down the leg, around the heel and for the length of the foot portion, while other of the wales 68 extend down the leg into the heel and terminate in the mark 60. It will also be seen that some of the wales 70 originate in the gore 54 and terminate in the mark 60 while other wales 72 originate in the gore 54 and extend downwardly into the foot. The wales 70 and 72 are angularly disposed with respect to the gore 54 and the mark 60 and the same number of wales are disposed between the edge of the stocking and the gore 54 down to the course 48.

In the forms of stockings illustrated in Figures 2, 3 and 4 inclusive, narrowing is initiated after the course 50 and where it is desired that the narrowing be effected to form sole narrowing marks 74, as near as possible to the stocking edge, a narrowing finger of one or more needles is used. Where one needle is used a ragged edge occurs, which is undesirable, but where two or more needles are used a continuous edge is formed such as shown in Figure 5 at 56.

In the stocking illustrated in Figure 2, the narrowing mark 74 is terminated at the course 77, and subsequent to said course the narrowing mark 78 is formed similar to the mark 60. Thus in this form of stocking the extreme edge wales or wale is continuous down the leg, around the heel and for the length of the foot, a portion of said wale being in the mark 74, other outer wales 79 adjacent to the edge will terminate in the mark 74, while certain inner wales 80 will terminate in mark 58. Wales 82 similar to wales 66 will extend down the leg, around the heel and for the length of the foot, and wales 84 will be formed similar to wales 70, and wales 86 will be formed similar to wales 72.

In the stocking illustrated in Figure 3, the mark 74 is maintained for a predetermined distance to effect the proper shaping of the heel, and part of the sole and the outermost edge wale or wales will extend down the leg, around the heel and for the

length of the foot, a portion of said wales being in the mark 74. Other wales 88 will be formed similar to wales 80, that is, terminating in mark 74 while others terminate in mark 58. Wale 90 will be formed terminating in the mark 74 while other wales 92 extend down the leg around the heel and for the length of the foot. Wale 86 similar to wales 86, Figure 2, will also be formed.

It is, of course, understood that the narrowing 74 may be made of such length that no wales will be formed between the gore 54 and mark 58 that extend down the leg around the heel and for the length of the foot, such as shown in Figure 4 where only wales 90 are formed between said gore and mark, but the edge wales as shown in Figure 5 at 56 do extend continuously.

It is to be understood that I do not wish to be limited by the exact embodiments of the process shown, which are merely by way of illustration and not limitation as various and other forms of the process will, of course, be apparent to those skilled in the art without departing from the spirit of the invention or the scope of the claim.

I claim:

A stocking having a leg portion, a heel portion and a foot portion, the stocking being so constructed that certain of the marginal edge wales thereof extend down the leg portion, around said heel portion and for the length of the foot portion, the heel portion being knitted with a reinforcing thread and provided with a gore formed by aligned apertures beginning at the start of the heel and extending substantially equidistant from the heel edge for a portion of the length of the gore, a heel mock fashioning being formed in the heel for a predetermined

distance causing certain wales adjacent said continuous wales to terminate therein, the mock fashioning terminating substantially at the course where the gore terminates, sole narrowing marks being formed in said sole starting at a point substantially outwardly of the wale in which the mock fashioning terminates and starting substantially at said course where the heel mock fashioning terminates, the length of said sole narrowing marks being such that substantially all of the wales between said gore and heel mock fashioning terminate in said sole narrowing marks, the reinforcing thread of said heel extending inwardly of the start of the gore for strengthening the stocking adjacent the gore.

EDWARD W. BOEDEKER.
